DESIGN FOR A STRAP FOR BELTS FOR PERSONAL WEAR OR SIMILAR ARTICLE

Morris Sachs, Rochester, N. Y., assignor to Hickok Manufacturing Company, Inc., Rochester, N. Y., a corporation of New York

Application January 6, 1936, Serial No. 60,462

Term of patent 3½ years

To all whom it may concern:

Be it known that I, Morris Sachs, a citizen of the United States, residing at Rochester, in the county of Monroe and State of New York, have invented a new, original, and ornamental Design for a Strap for Belts for Personal Wear or Similar Article, of which the following is a specification, reference being had to the accompanying drawing, forming part thereof.

The figure in the drawing is a plan view on a slightly enlarged scale of a portion of the strap having a plurality of ornamental cords along the opposite longitudinal edges of the body portion of the strap, the inner cord being comprised of a plurality of strands, one of which is of the same color as the central web portion of the strap, the shaded lines denoting contrasting color.

I claim:

The ornamental design for a strap for belts for personal wear or similar article as shown and described.

MORRIS SACHS.
